UNITED STATES PATENT OFFICE.

FLOYD K. EASTMAN, OF KOKOMO, INDIANA, ASSIGNOR TO CONCEALED DOOR CHECK COMPANY, OF KOKOMO, INDIANA, A CORPORATION.

DOORCHECK.

Application filed April 22, 1927. Serial No. 185,809.

This invention pertains to a door check, and particularly that type of overhead metallic check applicable to vehicle doors and the like, for limiting their outward swinging movement.

The principal object of this invention is to provide a check of the above character of simple and economical construction, and which will have a double spring bumper action when the door is moved to extreme open position and to extreme closed position.

The former action serves to absorb the shock when the door is thrown open, limiting the opening movement of the door, and as above noted, the shock will be absorbed by a centrally-positioned spring which is engaged and compressed from both ends toward the center.

Another feature of the invention resides in the arrangement of the shock absorbing spring in such position and manner that upon the door approaching closed position, the spring will be compressed so as to absorb any undue shock in slamming the door closed, and will also maintain the check under spring tension when the door is in closed position to prevent rattling thereof.

The full nature of the invention will be understood from the accompanying drawings and the following description and claims:

In the drawings, Figure 1 is a side elevation of the check in closed position mounted between the top of the door and the door frame. Fig. 2 is a plan view of the check showing it mounted upon the door and door frame with the door in partially opened position. Fig. 3 is the same as Fig. 2, showing the position of the check with the door in open position. Fig. 4 is a longitudinal section through the check and a portion of the door and frame with the door in extreme open position. Fig. 5 is the same as Fig. 4 showing the check with the door in closed position. Fig. 6 is a section taken on the line 6—6 of Fig. 4. Fig. 7 is a modified form with respect to the mounting of the check, showing it secured to a metal door frame.

In the drawings there is shown a vehicle door 10 mounted in the usual manner in a door frame 11 so as to swing outwardly therefrom upon the hinges 12. The door check comprises a pair of slotted links 13 and 14, said links being formed of metal and having

longitudinal slots 15 and 16 extending from one end to the other. The link 14 is pivotally connected with the upper part of the door frame 11 or header through the medium of an anchor plate 17 rigidly secured thereto by the screws 28 and countersunk in the surface thereof in the usual manner. The link 13 is similarly pivoted to the top of the door through the medium of the anchor plate 18, countersunk in the upper surface thereof. However, it may be herein noted that the anchoring device for pivotally securing said links to the door or door frame may be of any approved form or construction, such as an angle plate, a bolt, or as shown in the modified form of Fig. 7, which will be hereinafter described.

As best illustrated in Figs. 4 and 5, the anchor plates 17 and 18 have rigidly secured therein the cylindrical boss members 20 having spacing flanges 21 and internally screw threaded to receive the attaching screw 22. Thus the links are spaced from the anchor plates and the surface of the frame or door so as to pivot freely with respect thereto about the boss 20 which receives the strain so as to relieve the attaching screw 22 of any shearing action, as is well understood in the art.

The header of the frame is spaced from the top surface of the door to freely accommodate both links superimposed one upon the other, as shown in Fig. 1, the link 14 attached to the header being positioned immediately above the link 13. Said links are maintained in alignment and are adapted to slide in the same plane during their operation, being maintained in sliding connection with each other through the slide member 23. Said member is formed of reasonably heavy sheet metal clamped about both links so as to maintain them in alignment while freely permitting them to slide longitudinally with respect to each other. When thus positioned, the slots 15 and 16 register with each other, and have mounted therein, and within the sliding member 23, a coiled bumper spring 24, said bumper spring extending the length of the sliding member and being secured therein by a downwardly extending ear 25 stamped from the top of said member so as to extend inwardly and engage between adjacent coils of said spring substantially intermediate its ends. The ear 25 maintains the coil in proper position, leaving its opposite ends free to receive

the shock and be compressed inwardly toward each other.

From the above described construction, it will be noted that when the door is partially 5 opened, as illustrated in Fig. 2, it will cause said links to slide longitudinally of each other, while the tendency of the sliding member 23 will be to retain its position temporarily with respect to one of said links, whereby the 10 other link will be moved with respect thereto until the end of its slot will engage one end of the bumper spring 24. It will then force the sliding member to slide with respect to the other link as the door is further opened, 15 until the other end of the bumper spring engages the end of the slot on the other link, whereby the check will be in the position shown in Fig. 3. Upon reaching this position, the further movement of the door is arrested 20 and the shock of the arresting movement is absorbed by the compression of the bumper spring from both ends toward the center through the force applied thereto by its engagement between the ends of the slots 25 15 and 16.

As the door is moved to closed position, the links are permitted to freely slide in opposite directions, one over the other, until the opposite ends of the slots come in contact 30 with the ends of the spring, as shown in Fig. 5. This position is reached just prior to the door reaching the closed position, and such engagement arrests the movement of the door so as to prevent slamming thereof and causes 35 the springs to be compressed as the door is fully closed and latched. Upon the door being completely closed, the spring will be under tension between the ends of the slots so as to prevent any rattle of the structure caused 40 by vibration of the vehicle when moving with the doors closed.

As shown in Fig. 7, the header of the frame 11^a is formed of sheet metal and is provided with the same boss 20 with the flange 21 which 45 is secured to the anchor plate 18, said anchor plate being secured against the inner surface of the metal header between the flange 21 and the riveted end of the boss, all in accordance with the well known practice.

50 The invention claimed is:

1. A door check comprising a pair of links having longitudinal slots therein, means for pivotally anchoring each of said links at one end thereof, and a slide member slidably 55 supported by both of said links intermediate their ends for maintaining said links in alignment while permitting them to slide relative to each other.

2. A door check comprising a pair of links 60 having longitudinal slots therein, means for pivotally anchoring each of said links at one end thereof, a sliding member embracing both of said links for permitting them to slide relative to each other and maintain them in 65 alignment, and a bumper element mounted

in said slots for limiting the sliding movement of said links.

3. A door check comprising a pair of links having longitudinal slots therein, means for pivotally anchoring each of said links at one end thereof, a sliding member embracing both of said links for permitting them to slide relative to each other and maintain them in alignment, and a coiled spring housed in said sliding element and positioned 75 in said slots whereby its opposite ends will be engaged by the ends of said slots for limiting the sliding movement of said links with respect to each other.

4. A door check comprising a pair of links 80 having longitudinal slots therein, means for pivotally anchoring each of said links at one end thereof, a sliding member embracing both of said links for permitting them to slide relative to each other and maintain 85 them in alignment, a coiled spring housed in said sliding element and positioned in said slots whereby its opposite ends will be engaged by the ends of said slots for limiting the sliding movement of said links with respect to each other, and a projection formed 90 on said housing and engaging said spring intermediate its ends so as to maintain it in fixed relation with respect to said element.

5. The combination with a door frame and 95 a door hingedly mounted thereon, of a door check comprising a pair of links, an anchor for pivotally anchoring the end of one of said links to said door, an anchor for pivotally anchoring one end of the other link to the 100 frame, and a resilient member associated with said links intermediate their ends for resiliently limiting their sliding movement with respect to each other when the door is opened and resiliently limiting their movement with respect to each other upon the door being closed so as to prevent slamming thereof and maintain said check under spring tension.

6. The combination with a door frame and 110 a door hingedly mounted thereon, of a door check comprising a pair of links adapted to slide longitudinally in alignment with respect to each other, the free end of one of 115 said links being pivotally connected with said frame and the free end of the other link to said door, a slide member mounted thereon for maintaining them in aligned position during their relative sliding movement, and a compression spring associated with 120 said member for limiting the sliding movement of said links and absorbing the shock upon the door being opened to extreme position and adapted to be engaged and compressed for yieldingly retarding the sliding 125 movement of said links for preventing slamming of the door upon being closed and continuing to maintain said links under spring tension for preventing rattling thereof while the door is in closed position.

7. The combination with a door frame and a door hingedly mounted thereon, of a door check comprising a pair of links having longitudinal slots therein, said links being positioned in alignment and slidably longitudinal with respect to each other, the outwardly extending free ends of said links being pivotally connected to the door and frame respectively, a sliding member embracing the overlapping ends of said links, and a bumper spring mounted in said member and con-
- tained in said slots in position to be engaged by one pair of ends for limiting the sliding movement thereof and absorbing the shock upon the door being opened and by the other 15 ends of said slots for absorbing the shock and preventing slamming of the door upon being closed and maintaining said links under spring tension to prevent rattle.

In witness whereof I have hereunto affixed 20
my signature.

FLOYD K. EASTMAN.
